DESIGN FOR A COVER FOR A CIGARETTE CASE OR SIMILAR ARTICLE

Herbert H. Harris, New York, N. Y.

Application June 11, 1935, Serial No. 57,225

Term of patent 14 years

To all whom it may concern:

Be it known that I, Herbert H. Harris, a citizen of the United States and resident of New York, in the county of New York and State of New York, have invented a new, original, and ornamental Design for a Cover for a Cigarette Case or Similar Article, of which the following is a specification, reference being had to the accompanying drawing, forming part thereof.

In the drawing:

Fig. 1 is a perspective view of a cover for a cigarette case or similar article showing my new design.

Fig. 2 is a side edge view thereof.

Fig. 3 is an end edge view of the same.

I claim:

The ornamental design for a cover for a cigarette case, or similar article, substantially as shown.

HERBERT H. HARRIS.
